PISTON ROD

Application filed June 21, 1929, Serial No. 372,768, and in Switzerland July 2, 1928.

This invention relates to piston rods of the kind through which a cooling medium is circulated to the piston, for example, of a double-acting internal combustion engine. The cooling medium, though primarily intended to cool the piston of such engines, cools the piston rod in passing through it and in this way the material from which the rod is formed is exposed to severe heat stresses, as the temperture of the inner fibres of the rod is considerably lower than that of the outer fibres. As a result, the outer parts of the rod tend to expand to a greater extent than the inner parts though the actual expansion assumes a mean value midway between those of the inner and outer fibres of the rod. Hence the inner fibres are exposed to tension and the outer fibres to compression.

The stresses thus produced assume considerable dimensions over that portion of the piston rod which comes into contact with the very hot gases in the lower working chamber of a double-acting internal combustion engine. In the centre of the rod the temperture of the inner fibres may be say 70° C. and the outer fibres 120° C. and the difference, 50° C., results in heat stresses which are still quite admissible. In that portion of the piston rod nearest the piston, however, which is exposed to the highest temperatures, the outer fibres may be at as high a temperature as 300° C. and the temperture of the inner fibres not exceed 90° C., giving a difference of 210° C. which produces very considerable heat stresses.

The object of the invention is to reduce to within admissible limits this difference of temperature and the consequent heat stresses in such piston rods.

According to this invention the wall of the piston rod through which the cooling medium passes is reduced in thickness throughout that portion of its length which comes within the zone of the combustion chamber, or throughout a portion of such length.

Various constructions according to the invention are diagrammatically illustrated in the accompanying drawings, in which

Figure 1 is a vertical section through the cylinder of an internal combustion engine,

showing the upper portion of the piston rod, Figures 2 to 7 are similar sectional elevations of modified constructions of piston rod according to this invention, and

Figure 8 is a cross-section of the piston rod 55 illustrated in Figure 7.

In the double-acting internal combustion engine shown in Figure 1, the cylinder 1 is furnished with an upper cover 2 and with a lower cover 3 through which passes the piston rod 5 of the piston 4. In the lower cover is an annular space 6 to receive the usual stuffing box, and the piston rod is hollow and contains a pipe 8 through which cooling water is supplied to the piston, discharge of this cooling water taking place through the bore 7. The lower section or length A of the piston rod has a bore of the diameter a , the section or length B near the piston having a bore of the diameter b .

In the construction shown in Figure 2, that portion of the cooling water supply pipe 8 which lies within the widened portion of the bore, is thickened by having fitted to it an annular member 11 of aluminium or the like, 60 secured to the pipe by soldering, riveting, screwing or in any other suitable manner.

In the construction shown in Figure 3, the supply pipe 8 is provided with a widened portion 12, and in the modification shown in Figure 4 the bore of the piston is widened at 65 several points so as to form a number of internal circumferential ribs.

In Figure 5 an insulating pipe or sleeve 14 is provided extending over the length of 80 the widened portion of the bore. This pipe may be formed of heat insulating material or the space between the inner wall of the bore and the outer wall of the pipe may be wholly or partly filled with a heat conducting 85 substance, such as aluminium turnings.

In Figure 6 the throttling member 11 is mounted within a passage having a series of helical ribs and grooves 15, so that the discharge of cooling liquid follows a helical 90 path. In the further modification illustrated in Figures 7 and 8, longitudinal ribs 16 are provided on the inner wall of the bore 95 throughout the widened portion thereof.

The widening of the bore of the piston rod 100

according to the present invention increases the cooling action of the cooling medium on the outer fibres of the piston rod. Consequently the outer fibres of the rod will be at a temperature of say only 200° C. instead of 300° C. as hitherto, so that, assuming the temperature of the inner fibres to be 95° C., the difference of temperature between the inner and outer fibres will not exceed 105° C. The heat stresses in the piston rod will therefore be reduced about one-half of those which would exist if the bore of the piston rod were not widened.

The use of the throttling member shown in Figure 2 increases the speed of the cooling medium in the region where the piston-wall thickness is reduced, so that the walls of the piston rod are more rapidly cooled where their thickness is reduced, and the same effect can be obtained by the arrangement illustrated in Figure 3.

In the construction shown in Figure 4, the cooling surface of the inner wall of the piston rod 5 is increased and the cooling medium is forced to assume an eddying flow throughout the length provided with ribs 13. Both these factors increase the transmission of heat from the piston rod to the cooling medium.

In the construction illustrated in Figure 5, the insulating sleeve or pipe 14 prevents the cooling medium from coming into contact with the wall of the piston rod over the widened portion of its bore, and hence the wall of the rod 5 opposite the sleeve 14 will be at a higher temperature, but the difference of temperature between the inner and outer fibres will be less than is the case if the cooling water is allowed direct access against the inner wall of the widened bore, a reduction in heat stresses being thus ensured.

In the construction shown in Figure 6, the cooling medium is forced to follow a helical path through the conduit 15 and is thus conveyed deeply into the walls of the piston rod. In Figures 7 and 8 the longitudinal ribs 16 further serve to strengthen the rod and increase the area acted upon by the cooling medium.

In principle, that portion of the piston rod which comes into contact with the hot gases of the lower combustion chamber is furnished with a widened bore 9, and the desired result can be obtained in various ways. Thus, the section B over which the piston bore is widened could be increased or reduced, and instead of the cooling medium being supplied through the pipe 8 and discharged through the annular passage 7, the latter may be used to supply, discharge being permitted to take place through the pipe 8.

Satisfactory working conditions can be obtained if the diameter b of the widened bore 9 is equal to or greater than half the

diameter of the piston rod, so that the thickness of the remaining wall of the piston rod throughout the widened portion is a quarter or less of the diameter of the piston rod.

I claim:

1. In a double-acting internal combustion engine, a piston rod having an axial bore therein to permit the flow of a cooling medium therethrough, the wall of said bore being of lesser thickness over at least a portion of the length of the rod entering the cylinder than over the remaining length of the rod. 70

2. Apparatus according to claim 1 including means for increasing the heat transfer from the outer surface of the rod at the portion of the wall having a reduced thickness, said means being provided in the bore adjacent said portion of the wall. 75

3. Apparatus according to claim 1, wherein ribs are provided on the inner surface of the portion of the wall having a reduced thickness. 80

4. Apparatus according to claim 1, including means for increasing the rate of flow of the cooling medium over the portion of the wall having a reduced thickness, said means comprising a throttling member disposed in the bore adjacent said portion of the wall. 85

5. Apparatus according to claim 1, including means for deflecting the flow of cooling medium in its passage through the section of the bore adjacent the portion of the wall having a reduced thickness. 90

In testimony whereof I have affixed my signature. 100

CHARLES SCHAER.
